CLAIM

The ornamental design for an electrode patch array, as shown and described.

DESCRIPTION

FIG. 1 is a bottom perspective view of an electrode patch array showing my new design;

FIG. 2 is a top perspective view of the electrode patch array;

FIG. 3 is a bottom view of the electrode patch array;

FIG. 4 is a top view of the electrode patch array;

FIG. 5 is a side view of the electrode patch array;

FIG. 6 is a side view of the electrode patch array that opposes the side view of FIG. 5;

FIG. 7 is a front view of the electrode patch array;

FIG. 8 is a rear view of the electrode patch array; and,

FIG. 9 is an exploded perspective view of the electrode patch array.

1 Claim, 6 Drawing Sheets
